AUTOMATIC BROACHING MACHINE

Francis J. Lapointe, Ann Arbor, Mich.

Application August 8, 1930, Serial No. 474,024

16 Claims. (Cl. 90—33)

My invention has for its object to provide an efficient pull broaching machine for broaching articles in succession. It provides a means for manipulating the broach to enable ready placement of the work or articles operated upon. It also provides a structure that economizes as to floor space and enables the attendant to readily observe and adjust the manually operated or control parts of the machine. The major dimension 10 of the machine is vertical and the broach operates vertically which places the parts in position for ready control by the operator.

The invention also provides a means for supporting the broach in such a relation to the drawhead that the articles may be readily inserted in broaching position in succession to a point intermediate the drawhead and the cutting elements of the broach during the uninterrupted reciprocation of the broach. It also provides a means 20 for the delivery of the articles laterally from the broach operating mechanism.

The invention further provides means for automatically releasing the broach from, and reconnecting the broach to, the drawhead for the insertion of the articles in succession between the drawhead and the cutting elements of the broach, and a means, operated in unison with the operations of the broach for feeding the articles to be operated upon to the broach. The drawhead of 30 the broach is preferably located above the work plate and is operated by a fixed piston located well above the work plate, the drawhead being connected to the upper end of a reciprocable cylinder which is operated by the fixed piston where- 40 by rigidity of construction and maintenance of alignment is afforded.

The invention consists in other features and advantages which will appear from the following description and upon examination of the drawings. Structures containing the invention may 45 partake of different forms and may be varied in their details and still embody the invention. To illustrate a practical application of the invention, I have selected an automatic broaching machine embodying the invention as an example of the various structures and details thereof that contain the invention and shall particularly describe the selected structure hereinafter, it being understood that variations may be made and that certain 50 features of my invention may be used to advantage without corresponding use of other features, without departing from the spirit of the invention.

Fig. 1 is a front view of a broaching machine particularly referred to. Fig. 2 is a side view of 55 the machine. Fig. 3 illustrates a view of a sec-

tion of a controlling valve. Fig. 4 is a vertical section of the machine taken on the plane parallel to the side shown in Fig. 2. Fig. 5 illustrates a broken view of the broach lifting mechanism whereby the articles may be placed intermediate 60 the cutting elements of the broach and the drawhead to which the broach is coupled. Fig. 6 illustrates a perspective view of a socket that is manipulated by the broach lifting mechanism shown in Fig. 5. Fig. 7 is a view of a section taken on 65 the plane of the line 7—7 indicated in Fig. 2. Fig. 8 is a view of a section taken on the plane of the line 8—8 indicated in Fig. 7, and illustrates a transverse sectional view of an article receiving member which is operated by the feeding 70 mechanism of the machine. Fig. 9 is a view of a section taken on the plane of the line 9—9 indicated in Fig. 2, and illustrates a view of a section of a valve used for controlling the feeding mechanism of the machine. Fig. 10 is a diagrammatic 75 illustration of the pressure system used in connection with the broaching machine.

The broaching machine, selected as illustrative of the various embodiments of the invention, is provided with a work plate 1 that is secured to the 80 frame 2 of the machine. The broach drawhead 3 is connected to a reciprocable cylinder 4 and is provided with an automatic coupler 5 for connecting the broach 6 with the drawhead 3. The drawhead 3 is reciprocated above the work plate 85 1 by a hydraulic means located above the work plate for drawing the broach upward by the hydraulic pressure. Oil under pressure is directed from the upper end of the machine through a pipe 9 which communicates with the source of 90 supply of oil under pressure through the pipe 10 and a controlling valve. The pipe 9 fits within the cylinder head 11, the escape of the oil being prevented by a suitable packing nut 12.

The drawhead 3 is located at or below the 95 upper end of the cylinder and above the work plate 1. The piston 7 is also located above the work plate 1 and is supported in position by means of a fixed cylinder 13 having an exterior dimension that is slightly smaller than the interior dimension of the cylinder 4. The cylinder 13 is rigidly secured to the bed 14 of the machine and the lower end of the cylinder 4 is sealed by the packing ring 15 about the cylinder 13. The interior of the cylinder 13 is connected to a source 100 of supply of oil under pressure through a pipe 16 and a suitable controlling valve. The pressure of the oil is communicated through the 105 passageway 17 of the piston 7 to the underside of the piston of the cylinder and at a point above the 110

work plate. Thus the hydraulic operative means being located above the work plate and being rigidly held and guided in its movement by the ways 15 the drawhead 3 is rigidly maintained in alignment as it draws the work against the work plate and reciprocates the broach.

The movement of the oil through the pipes 10 and 16 to the piston 7 is controlled by means of a slide valve 20. The valve 20 is connected to a 10 pump 21 by means of a pipe 22. The pump 21 is located in the reservoir of oil 23 to which the oil is returned by means of the pipe 24, and from which the pump receives its oil.

The pipe 22 communicates with a passageway 15 25 formed in the valve casing of the slide valve 20. The slide valve 20 is provided with suitable pistons or ridges 26 so located on the slide valve as to direct the oil from the pump 21 into the pipe 10, and to permit the return of the oil 20 through the piston 7 and the pipes 16 and 24 to the oil reservoir 23. The oil from the pipe 10 enters the cylinder and the pressure forces it up, forcing the oil below the piston out through the pipe 16. Upon the return stroke of the cylinder 25 and the drawhead 3, the oil is directed through the pipe 16 into the cylinder 4 and through the piston 7 to the lower side of the piston, the oil located above the piston being forced to return to the reservoir 23 through the pipes 9 30 and 10.

The articles operated upon by the machine may be fed to the machine by a mechanism that varies in its details according to the character of the article that is to be shaped by the machine. 35 In the particular construction shown, bushings are fed sequentially to the machine and broached by the broach. They are directed to the lower side of the work plate from a suitable hopper through the pipe 27 that extends to the work 40 plate 1. A slidably supported plate 28 is located so as to close the end of the pipe 27 and prevent downward movement of the bushings in the pipe 27 during the placement of each succeeding bushing in position to be broached. The plate 28 is 45 shifted endwise to allow the bushings to drop from the pipe 27, one at a time, into a pocket 29 formed in the end of the plate 28 that is so located as to register with the end of the pipe 27 at the end of each succeeding outward movement 50 of the plate 28. The pocket 29 is substantially semicylindrical in form, having, however, plane surfaces that extend tangentially from the semi-cylindrical formation of the inner surface of the pocket. The edge portions of the pocket are 55 provided with means for releasably securing the bushings within the pocket until they are engaged by the cutting elements of the broach. The pocket may be provided with a pair of spring pressed balls 30 located in openings 31 having a 60 size, at their outer ends, to prevent the escape of the balls and yet permit the protrusion of portions of the balls into the interior of the pocket and so as to engage the bushing and also permit free movement of the balls within the bore of 65 the openings. The balls 30 are spring pressed by the springs 32. The outer ends of the openings 31 are closed by the threaded plugs 33 that subject the springs to the desired tension.

The pockets may be provided with a replaceable 70 stop 34. A recessed portion in the upper edge of the pocket, as at 35, retains the stop in position. The stop 34 is provided with an inwardly extending flange 36 for engaging the lower ends 75 of the bushings as they are sequentially dropped into the pocket. The location of the flange 36 is

such as to locate the upper ends of the bushings at a point in close proximity to the underside of the work plate 1. If desired, the location of the flange 36, which forms the limiting stop to the downward movement of the bushings from the pipe 27, may be made adjustable with reference to the pocket, or stops having different lengths may be located within the pocket 29, the length of the stop or the adjustment made depending upon the length of the bushings that are operated upon by the machine.

The plate 28 is reciprocated by means of a piston located in the cylinder 40, the plate being connected to a piston rod 41 by means of the link 42. The operation of the plate 28 is controlled by means of the slide valve 45, that alternately establishes connection between the source of supply of oil under pressure with the opposite ends of the cylinder 40. The opposite ends of the cylinder 40 are connected by means of the pipes 46 and 47 with the casing of the slide valve 45. The valve casing 44 is connected with the pump 48 through the pipe 49 to the passageway 50 within the valve casing, and the return pipe 51 interconnects the outlet passageway 52 of the valve casing with the reservoir 23. The pump 48 is located in the reservoir 23. The pumps 21 and 48 may be geared together and driven by a suitable motor.

Thus, by shifting of the slide valve 45, the pocket 29 is shifted between the points of registration with the pipe 27 and the opening 37 in the work plate. The articles fed through the pipe 27 may be thus located in alignment with the broaching head 3 of the machine. The movement of the slide valve 45 is so timed with the movement of the broach that opportunity is given for the cutting elements of the broach to engage the work and, by the pressure exerted in the cutting operation, secure and hold the work in position against the under side of the work plate 1 before the slide plate 28 is returned. When the work is so engaged, the slide plate 28 may be returned to a point such that the pocket 29 will receive the succeeding piece of work, the pocket 110 being drawn from the article. Thus, as the broach is operating on the work that has been delivered to it, the plate 28 is returned to receive the succeeding article and, subsequently, the succeeding article is positioned so that it will be 115 engaged by the broach.

In order that the broaching machine may finish substantially closed bodies by means of a pull broach, it is necessary that the broach be disconnected from the drawhead 3 in order that the 120 work may be positioned. In order that the broach may be released from the drawhead 3, an automatic coupler 5 is provided to disconnect the broach upon the return stroke of the drawhead 3. Any suitable automatic coupler may be used. In 125 the particular form of construction shown, a lever 55 is pivotally connected to a shell 56 by means of the pin 57. The shell 56 is provided with a recess 58 having inclined surfaces 59, and a pair of dogs 60 having surfaces that correspond to the inclined surfaces 59 are located within the recess 58 and vertically movable therein so as to spread the dogs 60 when they are raised along the inclined surfaces 59. The lower ends of the dogs 60 are operated upon by cross members 61 that are connected to the lever 55 and so that when the lever 55 is rotated on the axis of the pin 57, the dogs 60 will be raised and also will separate from each other to release the end of the broach located between the dogs 60. 130 135 140 145 150

The dogs 60 are provided with engaging teeth 62, while the upper end of the broach may be provided with corresponding engaging teeth, the teeth of the dogs and the teeth 63 of the broach 5 interengage when the lever 55 is released and the upper end of the broach is located between the dogs. Preferably, the interengaging teeth of the dogs and the broach are made in the form of V-threads which provides ready and secure inter-10 engagement between the parts.

As the drawhead 3 completes its return stroke, the lever 55 is engaged by a latch 65 that is pivotally supported on a suitable bracket or on suitable lugs 66. One end of the latch is free to move upward as the end of the lever 55 is moved upward in the upward movement of the drawhead 3. As the drawhead 3 completes its stroke the latch 65 releases the dogs 60 and allows the broach to drop through the opening 37 of the work plate.20 Preferably, the lower end of the broach 6 is received by means of a socket 70 into which the broach 6 is stepped, as it is released from the drawhead, the socket 70 being connected to a means for permitting its descent to a point below the lower end of the work that may be placed against the underside of the work plate.25

The socket 70 is adjustably connected to a cylinder 71 by means of the bolts 72 and a bracket 73. The socket 70 is supported on the bracket 73. The bracket 73 is adjusted according to the length of the broach 6 used in broaching the bushings to permit withdrawal and reconnection of the broach from and with the drawhead 3 and through the work. The cylinder 71 is provided with a fixed piston 74, the piston 74 being provided with a hollow piston rod 75, that communicates with the interior of the upper end of the cylinder through the openings 76. The upper end of the cylinder is sealed by a suitable packing 35 nut 77. The piston rod 75 is connected with a source of supply of oil under pressure, by means of the pipe 78, whereby the cylinder may be raised to raise the broach 6, and to push the dogs 60 of the coupler 5 to one side and enable the connection of the broach with the drawhead.45

The cylinder 71 is guided in its movements by means of a pair of sleeves 79 slidably located on rods 80 that depend from a bracket 81 that is connected to the frame 2 of the machine.

50 Preferably, the cylinder 71 is controlled in its operations by means of the slide valve 20. It is connected to the pipe 10 and the oil pressure is transmitted to the upper end of the cylinder 71 as well as to the cylinder 4. This will first raise the cylinder 71 to connect the broach to the drawhead by reason of the fact that the cylinder 71 is much lighter in weight and merely carries the broach 6. Upon completion of the stroke of the cylinder 71, the cylinder 4 will immediately be raised to draw the broach through the work plate. The cylinder 71 will thus be held in its raised position by the pressure of the oil in the pipe 10 which produces the upward movement of the cylinder 4. When the slide valve 20 is shifted 55 to connect the pump 21 with the under side of the piston 7, the pressure of the oil produced in the pipes 9 and 10 by the forced downward movement of the pressure of the oil below the piston 7, will still maintain sufficient pressure within the cylinder 71 to hold the cylinder in its uppermost position and in position to receive the lower end of the broach 6. When the lever 55 is engaged by the latch 65 the lower end of the broach is located within or near the upper end of the 60 socket 70 and the broach is dropped to the bottom

of the socket. Upon the completion of the downward movement of the cylinder 4, the pressure within the cylinder 71 is sufficiently reduced such that the weight of the cylinder 71 and the broach 6 is sufficient to press the oil through the pipe 78, the valve casing of the slide valve 30, and the pipe 24 to the reservoir 23. After the broach has descended well below the work plate 1, an article may be placed intermediate the work plate and the cutting edges of the broach by the operation of the slide plate 28. The upper end of the broach may then be raised through the work plate and into the coupling to connect the broach 6 with the drawhead. This will be produced by the shifting of the slide valve 20 which again directs the oil pressure into the cylinders 71 and 4. Thus the cylinder 71 moves in advance of the cylinder 4 because of the difference in the weight of the two cylinders and because of the difference in the cross sectional area of the cylinders proportionate to the load that they carry.80

The movements of the slide valves of the machine, to bring about the sequential operations of the machine, is automatically controlled by a means that operates in unison with the movements of the cylinder 4. An arm 84 is connected to the upper end of the cylinder 4. It is provided with a collar 86 that surrounds a rod 87 that is vertically movable within a bracket 89 and is connected to and supported by a link 93 and an arm 94. The arm 94 is secured to a shaft 99 that is supported in the frame 2 of the machine. An arm 82 is also connected to the shaft 99 and operates the rod 83 which is connected to the slide valve 20. Movement of the rod 87 thus operates 100 through the elements, just described, to shift the slide valve 20 and to direct the oil under pressure from the pump 21 into one or the other of the pipes 10 or 16. The change is produced by the collar 86 which engages one or the other of the 105 adjustable collars 85 secured to the rod 87. The engagement of the collars occurs at the points where it is desired to change the direction of the stroke of the drawhead 3.110

The slide plate 28 which is operated by the oil pressure within the cylinder 40, is brought about by the movement of the rod 88 which is also connected to the arm 84. The rod 88 is provided with an arm 90 that engages the upper end of the rod 91 to which the slide valve 45 is connected. The slide valve 45 and the rod 91 are spring 120 pressed by the spring 92 located intermediate the valve casing 44 and a collar located on the rod 91. When the rod 91 is pushed downward by the engagement of the arm 90, the slide valve is shifted 125 so as to connect the inner end of the cylinder 40 with the pump 48 and cause the plate 26 to be moved towards the opening 37 in the work plate 1. This is near the completion of the return movement of the drawhead 3 and shortly before the time that the broach is allowed to drop through the opening 37 by the engagement of the lever 55 with the latch 65. The lower collar 85 is then engaged by the collar 86 located on the end of the arm 84 which changes the position 130 of the slide valve 20 and the cylinder 71 is raised to raise the broach 6 through the bushing located in the pocket 27 of the plate 28 and into the coupling 5. This is when the cylinder 71 has completed its upward stroke, whereupon the pressure of the oil within the pipe 10 operates the cylinder 4 which is raised to draw the broach through the bushing located within the pocket 29.135

The arm 90 is drawn from the upper end of the spring pressed rod 91 but the spring pressed rod

91 is held in its position to maintain the pocket beneath the opening 37 of the work plate 1 until the cutting elements of the broach substantially cover the inner surface of the bushing whereby 5 the bushing will be held by the broach against the under side of the face plate and in alignment for completion of the cutting operations of the broach, whereupon the pocket and the slide plate may be returned for the receipt of the succeeding bushing in the pocket. The slide plate 28 is maintained in a position to hold the bushing in alignment during the movement of the teeth of the smaller end of the broach through the bushing by the pressure of the oil exerted by the 10 pump 48, the spring pressed rod 91 being held down by means of a latch 95. The latch 95 is slidably supported on a bracket 96 which is connected to the frame of the machine. The latch is spring pressed by means of the spring 97 located intermediate the end of the latch 95 and the outer end of the bracket 96. The spring pressed rod 91 is provided with a conical collar 98 which operates to force the latch 95 outward away from the rod 91 when the rod 91 is forced 25 down by the arm 90 until the conical collar 98 is located below the lower edge or surface of the latch 95, whereupon the collar and the rod 91 are engaged by the latch 95 and held in a position to permit transmission of fluid pressure from 30 the pump 48 to the inner end of the cylinder 40. When the rod 88 is raised by upward movement of the cylinder 4, the rod 91 is held by the latch 95 until the latch 95 is engaged by the raised boss or cam part 100 located on the rod 88. The rod 35 88 moves through the outer end of the bracket 96 and through an opening 101 formed in the latch 95. The latch 95 is pressed by the spring 97 against the rod 88 when the conical collar 98 is located beneath or above the latch 95. The 40 rod 88 affords a limiting stop for the movement of the latch 95 under the pressure on the spring 97. As the cylinder 4 and the rod 88 are moved upward, the cam 100 operates to shift the latch 95 from its engagement with the conical collar 98 to release the spring 92 and cause the slide valve 45 to shift its position which connects the outer end of the cylinder 40 with the pressure pump 48. The plate 28 is then moved outward until the pocket 29 is located in alignment with 50 the pipe 27 and receives the succeeding bushing to be operated upon by the broach. The cycle of operations thus continues, the machine automatically operating to broach cut the articles in succession.

55 Preferably, the machine is substantially entirely enclosed by means of the frame 2 which constitutes an enclosing shell. Also, the front of the machine may be covered by means of the plates 105. If desired, the machine may be provided with a platform 106 on which the operator may stand. Also, a sloping shelf 107 is located beneath the work plate 1 which operates to discharge the bushings from the machine when they are released from the broach, that is, when the broach has been drawn through each bushing. The bushings drop and strike the inclined shelf 107 which causes their outward movement. Suitable troughs or chutes may be used for conveying the bushings to a suitable delivery point.

70 Preferably, the shelf 107 is provided with an opening 108 in which the upper end of the broach 6 is located when the socket 70 is located in its lowermost position and thus maintains the broach 6 in alignment with the socket 70 and the coupling 5 and so that when the broach 6 is raised

by operation of the cylinder 71, the upper end of the broach will be directed to the coupling 5 to be engaged by the dogs 60.

The socket 70 is, preferably, formed of a collar 112 and a base 109 on which it is supported 80 and to which it is connected by the legs 110. The inner surface of the collar 112 is, preferably, conical, the larger diameter being at the upper end of the socket 70. This forms a mouth for receiving the lower end of the broach 6 when it is 85 discharged from the drawhead 3. The space between the collar 112 and the base 109 of the socket 70 affords a means for the discharge of the metal shavings that may drop through the opening 90 formed in the shelf 107. Preferably, the surface of the base 109, beneath the collar 112, is formed conical or convex to discharge the shavings from beneath the collar into the bed of the machine. Also, in order to prevent the shavings from collecting on the hollow piston rod and the cylinder 95 90 100 105 110 115 120 125 130 135 140 145 150

71, a sheet metal apron 113 is located over the cylinder 71. In order to enable the escape of any oil that may pass the piston 74 and into the lower end of the cylinder 71, a pipe 115 is connected to the lower end of the cylinder 71 and preferably extends upward to a point well above the base of the machine to prevent the oil that collects in the base of the machine from conveying any particles of the shavings into the cylinder 71 upon the downward stroke of the piston 105 and at the same time provide a vent for free downward movement of the cylinder. The upper end of the pipe 115 is, preferably, turned downward as at 116, to prevent any of the shavings, falling from the shelf 107, from entering the pipe 110 115.

I claim:

1. In a pull broach machine, a work plate, an upright cylinder, a broach drawhead located above the work plate and connected to the cylinder at the upper end of the cylinder, a fixed piston located above the work plate and within the cylinder the axis of the piston extending vertically, a stationary pipe extending through the upper end of the cylinder, a second cylinder extending through the lower end of the first named cylinder and connected to the piston, means for directing oil under pressure alternately through the said stationary pipe and the second named cylinder to opposite sides of the piston.

2. In a pull broach machine for broaching articles, a work plate, a pull broach, a drawhead, a cylinder and piston for operating the drawhead, a coupler for connecting the broach to the drawhead, a second cylinder and piston for moving the broach into operative connection with the coupler, a member for positioning the articles in broaching position between the drawhead and the broach when the broach is separated from the drawhead, a third cylinder and piston for operating the said member, a source of supply of fluid under pressure, valves for controlling the movement of the fluids to the said cylinders, means movable with the drawhead for actuating the said valves to produce operative movements of the said cylinders and pistons.

3. In a pull broach machine, a work plate, a pull broach, a drawhead located above the work plate, a cylinder and piston for operating the drawhead, a coupler for connecting the broach to the drawhead, a second cylinder and piston for lifting the broach into operative connection with the coupler, a member for positioning the articles in broaching position between the drawhead and the broach when the broach is sepa-

- rated from the drawhead, a third cylinder and head, a pull broach, the drawhead having means for connecting the pull broach to the drawhead, means for supporting the broach in spaced relation with respect to the drawhead and for moving the broach to connect the broach with the drawhead, means for feeding the work between the broach and the drawhead, and means having a part operated by the drawhead for producing operation of the said feeding means. 80
- 10 4. In a pull broach machine, a work plate, a pull broach, a drawhead located above the work plate, a cylinder and piston for operating the drawhead, a coupler for connecting the broach to the drawhead, a second cylinder and piston for lifting the broach into operative connection with the coupler, a member for positioning the articles in broaching position below the work plate and between the drawhead and the broach when the broach is separated from the drawhead, a third cylinder and piston for operating the said member, a source of supply of fluid under pressure, valves for controlling the movement of the fluids to the said cylinders, means movable with the drawhead for actuating the said valves to produce operative movements of the said cylinders and pistons, a shelf inclined to the vertical for directing the articles from between the drawhead and the pull broach, the shelf having an opening 20 for guiding the broach as it is lifted by the said second cylinder and piston. 95
- 15 5. A pull broach machine, a work plate, a pull broach, a drawhead, a cylinder and piston for operating the drawhead, a coupler for connecting the broach to the drawhead, a second cylinder and piston for moving the broach into operative connection with the coupler, a member for positioning the articles in broaching position with reference to the broach, a third cylinder and piston for operating the said member, a source of supply of fluid under pressure, valves for controlling the movement of the fluid to the said cylinders, and means for operating the said valves to produce sequential operation of the pistons and cylinders. 100
- 20 6. In a pull broach machine, a work plate, a broach drawhead, means for reciprocating the drawhead to and from the work plate, a pull broach, the drawhead having means for automatically connecting and disconnecting the broach to and from the drawhead, means for receiving the broach from the drawhead and for supporting the broach in displaced relation with respect to the drawhead, the machine having a movable member, means for moving the member during the movement of the drawhead, automatic means operated by the said movable member for feeding the work to a point between the broach drawhead and the pull broach when the broach is separated from the drawhead and when the drawhead is located in proximity to the work plate. 105
- 25 7. In a pull broach machine, a work plate, a broach drawhead, a pull broach, means for supporting the broach in displaced relation with respect to the drawhead, the machine having a movable part operable periodically according to the movements of the drawhead, means for feeding the work between the broach and the drawhead and having a member actuated by the said movable part of the machine when the broach is displaced from the drawhead for causing operation of said means, and means for moving the broach to connect the broach to the drawhead. 110
- 30 8. In a pull broach machine, a work plate, a broach drawhead, means for operating the draw- 115
- 35 9. In a pull broach machine, a work plate, a pull broach, a drawhead, means for operating the drawhead, a pull broach, the drawhead having means for connecting the pull broach to the drawhead, means for supporting the broach in spaced relation with respect to the drawhead and for moving the broach to connect the broach with the drawhead, means for feeding the work between the broach and the drawhead, and means operated periodically and according to the movement of the drawhead for causing operation of the said feeding means. 120
- 40 10. In a pull broach machine, a work plate, a broach drawhead, means for operating the drawhead, a pull broach, the drawhead having means for connecting the pull broach to the drawhead, means for supporting the broach in spaced relation with respect to the drawhead and for moving the broach to connect the broach with the drawhead, means for feeding the work between the broach and the drawhead, and means operated upon the displacing movement of the broach for causing the operation of the said feeding means. 125
- 45 11. In a pull broach machine, a work plate, a pull broach, a drawhead, a cylinder and piston for operating the drawhead, an automatic coupler for connecting the broach to the drawhead, a second cylinder and piston for moving the broach into operative connection with the coupler, a source of supply of fluid under pressure, a member having a passageway for connecting the cylinders to the said source to produce broach movement of one cylinder and a working stroke of the broach by the other cylinder, the said passageway forming a return passageway from the said cylinders, the pressure in the said passageway during the working stroke and the return stroke operating to retain the second cylinder and piston in the broach delivering position. 130
- 50 12. In a pull broach machine, a work plate, a pull broach, a drawhead, a cylinder and piston for operating the drawhead, an automatic coupler for connecting the broach to the drawhead, a second cylinder and piston for moving the broach into operative position with the coupler, a source of supply of fluid under pressure, a member having a passageway for directing fluid to the cylinders from the said source and directing fluid from the cylinders to the said source, one of the movable parts operated by the second cylinder and piston having a proportionate weight materially less than the movable part of the other cylinder and piston as compared to the ratio of the bores of the cylinders for producing movement of the lighter weight cylinder in advance of the heavier weight cylinder when the passageway conducts fluid from the source to the cylinders to produce a broach movement of the other cylinder in advance of the working stroke of the first named cylinder. 135
- 55 13. In a pull broach machine, a work plate, a pull broach, a drawhead, a cylinder and piston for operating the drawhead, an automatic coupler for connecting the broach to the drawhead, a second cylinder and piston for moving the broach 140
- 60 14. In a pull broach machine, a work plate, a pull broach, a drawhead, a cylinder and piston for operating the drawhead, an automatic coupler for connecting the broach to the drawhead, a second cylinder and piston for moving the broach 145
- 65 15. In a pull broach machine, a work plate, a pull broach, a drawhead, a cylinder and piston for operating the drawhead, an automatic coupler for connecting the broach to the drawhead, a second cylinder and piston for moving the broach 150
- 70 16. In a pull broach machine, a work plate, a pull broach, a drawhead, a cylinder and piston for operating the drawhead, an automatic coupler for connecting the broach to the drawhead, a second cylinder and piston for moving the broach
- 75 17. In a pull broach machine, a work plate, a pull broach, a drawhead, a cylinder and piston for operating the drawhead, an automatic coupler for connecting the broach to the drawhead, a second cylinder and piston for moving the broach

into operative position with the coupler, a source of supply of fluid under pressure, a member having a passageway for directing fluid to the cylinders from the said source and directing fluid from the cylinders to the said source, one of the movable parts operated by the second cylinder and piston having a proportionate weight materially less than the movable part of the other cylinder and piston as compared to its ratio of the 5 bores of the cylinders for producing movement of the lighter weight cylinder in advance of the heavier weight cylinder when the passageway conducts fluid from the source to the cylinders to produce a broach movement of the other cylinder 10 in advance of the working stroke of the first named cylinder, the pressure in the said passageway produced by the return stroke of the heavier cylinder and piston operating to retain the second cylinder in the broach delivering position to receive the broach upon substantially the completion 15 of the return of the first named cylinder.

14. In a pull broach machine, a work plate, a pull broach, a drawhead, a cylinder and piston for operating the drawhead, an automatic coupler for connecting the broach to the drawhead, a second cylinder and piston for moving the broach into operative position with the coupler, a source of supply of fluid under pressure, a member having a passageway for directing fluid to the cylinders 20 from the said source and directing fluid from the cylinders to the said source, one of the movable parts operated by the second cylinder and piston having a proportionate weight materially less than the movable part of the other cylinder and piston as compared to its ratio of the 25 bores of the cylinders for producing movement of the lighter weight cylinder in advance of the heavier weight cylinder when the passageway conducts fluid from the source to the cylinders to produce a broach movement of the other cylinder 30 in advance of the working stroke of the first named cylinder, the pressure in the said passageway produced by the return stroke of the heavier cylinder and piston operating to retain the second cylinder in the broach delivering position to receive the broach upon substantially the completion 35 of the return of the first named cylinder.

15. In a pull broach machine, a work plate, a pull broach, a drawhead, a cylinder and piston for operating the drawhead, a coupler for connecting the broach to the drawhead, a second cylinder and piston for moving the broach into operative connection with the coupler, a source of supply of fluid under pressure and a reservoir for supplying fluid to the said source of supply of fluid under pressure, a member having a passageway connected to the cylinders, means for connecting the said passageway to the said source of supply of fluid under pressure and to the said reservoir, the said means operating to connect the 40 cylinders to the said reservoir upon the completion of the working stroke of the first named cylinder and piston, the return stroke of the first named cylinder operating to create a pressure for the retention of the second cylinder and piston in the broach delivering position.

16. In a pull broach machine, a work plate, a drawhead located above the work plate, a cylinder and piston for operating the drawhead, a pull broach, a coupler for connecting the broach to the drawhead, a member having a socket for supporting the broach, a second cylinder and piston operable by a pressure less than that required for operation of the first named cylinder and for raising the member to place the broach 45 in operative connection with the coupler, a source of supply of fluid, means for subjecting the fluid to a pressure for operating the cylinders and pistons, a valve for controlling the flow of liquid from the said means to the said cylinders to first move the second cylinder and upon completion of the movement of the second cylinder to move the first named cylinder, and to retain the second named cylinder in its position until the completion 50 of the stroke of the first named cylinder and for permitting the return of the fluid from the first named cylinder to the source and maintain a pressure in the second named cylinder until the first named cylinder has completed its return stroke, the second named cylinder completing its return movement by the weight of the broach and parts connected therewith upon the completion of the return stroke of the first named cylinder.

of the pressure produced by the forced return of the first named cylinder.

15. In a pull broach machine, a work plate, a pull broach, a drawhead, a cylinder and piston for operating the drawhead, a coupler for connecting the broach to the drawhead, a second cylinder and piston for moving the broach into operative connection with the coupler, a source of supply of fluid under pressure and a reservoir for supplying fluid to the said source of supply of fluid under pressure, a member having a passageway connected to the cylinders, means for connecting the said passageway to the said source of supply of fluid under pressure and to the said reservoir, the said means operating to connect the cylinders to the said reservoir upon the completion of the working stroke of the first named cylinder and piston, the return stroke of the first named cylinder operating to create a pressure for the retention of the second cylinder and piston in the broach delivering position.

16. In a pull broach machine, a work plate, a drawhead located above the work plate, a cylinder and piston for operating the drawhead, a pull broach, a coupler for connecting the broach to the drawhead, a member having a socket for supporting the broach, a second cylinder and piston operable by a pressure less than that required for operation of the first named cylinder and for raising the member to place the broach in operative connection with the coupler, a source of supply of fluid, means for subjecting the fluid to a pressure for operating the cylinders and pistons, a valve for controlling the flow of liquid from the said means to the said cylinders to first move the second cylinder and upon completion of the movement of the second cylinder to move the first named cylinder, and to retain the second named cylinder in its position until the completion of the stroke of the first named cylinder and for permitting the return of the fluid from the first named cylinder to the source and maintain a pressure in the second named cylinder until the first named cylinder has completed its return stroke, the second named cylinder completing its return movement by the weight of the broach and parts connected therewith upon the completion of the return stroke of the first named cylinder.
